US0D1113920S

(12) **United States Design Patent** (10) **Patent No.:** **US D1,113,920 S**
(45) **Date of Patent:** **** Feb. 17, 2026**

(54) **COMBINED INTERACTIVE DISPLAY AND USB HUB**

(71) Applicant: **Shenzhen Yishilian Technology Co., Ltd.**, Guangdong (CN)

(72) Inventor: **Binbin Su**, Guangdong (CN)

(**) Term: **15 Years**

(21) Appl. No.: **29/969,223**

(22) Filed: **Oct. 21, 2024**

(30) **Foreign Application Priority Data**

Sep. 13, 2024 (CN) 202430587909.6

(51) **LOC (15) Cl.** **14-02**

(52) **U.S. Cl.** USPC **D14/371; D14/434**

(57) **CLAIM**

The ornamental design for a combined interactive display and USB hub, as shown and described.

DESCRIPTION

FIG. 1 is a perspective view of a combined interactive display and USB hub showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left, bottom perspective view thereof.

FIG. 9 is an enlarged detail view of area 9 shown in FIG. 1.

FIG. 10 is an enlarged detail view of area 10 shown in FIG. 3; and,

FIG. 11 is an enlarged detail view of area 11 shown in FIG. 8.

The broken lines in the drawings depict portions of the combined interactive display and USB hub that form no part of the claimed design.

1 Claim, 11 Drawing Sheets
